UNITED STATES PATENT OFFICE.

ARNOLD MOETTELLI, OF OBERWINTERTHUR, SWITZERLAND, ASSIGNOR, BY MESNE ASSIGNMENTS, TO DRY QUENCHING EQUIPMENT CORPORATION, OF NEW YORK, N. Y., A CORPORATION OF DELAWARE.

APPARATUS FOR COOLING INCANDESCENT COKE.

Application filed February 7, 1925, Serial No. 7,519, and in Switzerland April 19, 1924.

This invention relates to apparatus for cooling incandescent coke of the type in which the cooling gas is passed in a closed circuit through the coke in a container and over a heat exchange device the circulation being caused by some form of pump or fan or by a combination of the two. The object of the invention is to avoid explosive combustion taking place within the container in consequence of the gas given off in the container by insufficiently distilled coke forming an explosive mixture with air when a certain quantity of fresh air is suddenly introduced into the container, for example, when a fresh quantity of coke is being charged or when cooled coke is being withdrawn.

According to this invention the apparatus is provided with an air-inlet valve from which the current of cooling gas is continuously supplied with a small quantity of fresh air in such a manner that the air passes to combustion with the combustible gases immediately they are formed and without disturbing the cooling operation. The air inlet valve is preferably adjustable and an outlet valve for the cooling gases which is also formed adjustable may be provided these two valves being arranged in connection with one another so that the two valves can operate simultaneously.

In a preferred arrangement the air inlet valve is fitted in the conduit through which the cooling gases pass from the heat exchange device into the coke container where the pressure within the conduit is less than that outside it, this valve being disposed on the suction side of the circulating pump where such is provided so that in either case the air is drawn in by the current of cooling gases.

One construction according to this invention is diagrammatically illustrated by way of example in the accompanying drawing.

The apparatus illustrated comprises a container *a* to receive the incandescent coke and a steam generator *b*, the cooling of the coke being effected in the known manner by driving the gaseous contents of the container and the heating chamber which contains the generator in a closed circuit by means of a blower *c* and circulating pipe *e* through the coke within the container and over the heating surfaces of the generator, the heat given

off by the coke being thus utilized to generate steam. The incandescent coke is introduced through the opening *f* provided with a cover into the container and is discharged therefrom after being cooled through an outlet *g* provided with a suitable controlling door.

If the coke has been insufficiently distilled during the distillation process, combustible gases, especially hydrogen, may escape into the cooling chambers together with the cooling gases passed through the coke, and this may produce explosions within the apparatus. To prevent such explosions, according to this invention the apparatus is provided with an air inlet valve *h* in the suction pipe of the blower and with an outlet valve *i* between the coke container and steam generator. The air inlet valve ensures a constant supply of fresh air to the cooling gases, owing to the low pressure which obtains in the suction pipe, and this air combines with the combustible gases contained in the coke on mixing with the cooling gases and thus prevents these gases subsequently forming an explosive mixture. The cooling gas outlet valve *i* compensates for the increase in the cooling gases so produced and the escape of cooling gases into the atmosphere takes place immediately, as the cooling gas pressure at this point is higher than that of the atmosphere. Both the valves *h* and *i* are preferably provided with some adjusting mechanism so that the air supplied is just sufficient to render harmless the combustible gases present in the coke.

Having now particularly described and ascertained the nature of my said invention, as communicated to me by my foreign correspondents, and in what manner the same is to be performed, I declare that what I claim is:—

1. Apparatus for cooling incandescent coke comprising a container for the coke, a heat exchanging device connected thereto to form a closed circuit, means for circulating an inert gas in said closed circuit through the coke container and the heat exchanging device, and a valved air inlet adapted to admit a small quantity of fresh air to said closed circuit to cause consumption of any combustible gases given off in the container by insufficiently distilled coke.

and thereby prevent the formation of an explosive mixture when air is suddenly admitted to the container as by introduction of coke to the container or withdrawal of coke from the container.

2. Apparatus for cooling incandescent coke in accordance with claim 1 in which the air inlet valve is adjustable.

3. Apparatus for cooling incandescent coke in accordance with claim 1 in combination with a valved outlet adapted to allow

escape of gas from the circuit when air is admitted by the air inlet valve.

4. Apparatus for cooling incandescent coke in accordance with claim 1 in which ¹⁵ the air inlet is connected into the suction side of the means for circulating an inert gas in the closed circuit.

In testimony whereof I have affixed my signature.

ARNOLD MOETTELI.
